UNITED STATES PATENT OFFICE.

OSCAR FRÖLICH, OF BERLIN, GERMANY, ASSIGNOR TO SIEMENS & HALSKE,
OF SAME PLACE.

OZONE-TUBE.

SPECIFICATION forming part of Letters Patent No. 487,390, dated December 6, 1892.

Application filed November 14, 1891. Serial No. 411,848. (No model.) Patented in Germany March 25, 1891, No. 59,565; in France May 26, 1891, No. 213,696; in Belgium May 26, 1891, No. 95,001, and in Italy May 26, 1891, No. 29,781/296.

To all whom it may concern:

Be it known that I, OSCAR FRÖLICH, a citizen of Switzerland, residing at Berlin, Prussia, Germany, have invented certain new and useful Improvements in Ozone-Tubes, (for which Letters Patent were received in France, No. 213,696, dated May 26, 1891; in Belgium, No. 95,001, dated May 26, 1891; in Germany, No. 59,565, dated March 25, 1891, and in Italy, No. 29,781/296, dated May 26, 1891;) and I do hereby declare the following to be a full, clear, and exact description of the invention, such as will enable others skilled in the art to which it appertains to make and use the same.

This invention relates to improvements in tubes or apparatus for ozonizing air and gases, said improvements referring more particularly to a novel disposition of the conducting coatings or surfaces, the character of the dielectric material employed, and the general construction of the apparatus.

Prior to the invention of the improvements herein referred to the dielectric material and ozonizing-chamber were interposed between the conducting coatings or surfaces charged with electricity of opposite sign. By change of the charges in said coatings there were produced in the ozonizing-chamber electric discharge-currents leading directly from one coating or surface to the other. In the event of the apparatus being of cylindrical form the disadvantages were increased, since it was necessary to provide for the internal surface which was covered or surrounded by the dielectric layers a conducting connection to the outside, thereby augmenting the liability of difficulty from imperfect insulation. To obviate both the charges noted, I locate both the electrical coatings or surfaces on one side of the dielectrical layer and employ in connection therewith and on the opposite side of said layer a third conducting-body properly insulated and having no connection with the said coatings or surfaces.

Prior to the invention of the improvements herein referred to the electrical arrangement of such apparatus consisted in interposing between two conducting-coatings charged with electricity of opposite sign one or two dielectric layers and the layer of gas to be

ozonized. By the change of the charges on the first-named coatings there were produced in the layer of gas electrical discharge-currents leading directly from the one coating or surface to the other. In the event of the apparatus being of cylindrical form the disadvantages were increased, since it was necessary to provide for the internal surface, which was covered or surrounded by the dielectric layer, a conducting connection to the outside, thereby augmenting the liability of difficulty from imperfect insulation. To obviate the objections noted, I locate both of the electrical coatings or surfaces on one side of the dielectric layer and employ in connection therewith and on the opposite side of said layer a third conducting-body properly insulated and having no connection with the said coatings or surfaces.

In the drawings accompanying this specification, Figures 1 and 2 are a longitudinal section and plan view, respectively, showing in detail the relative position of the essential parts according to my improvements. Figs. 3 and 4 are a vertical and horizontal sectional detail view, respectively, showing the essential parts illustrated in Figs. 1 and 2 modified by being arranged in cylindrical form. Fig. 5 is a vertical elevation, partly in section, also showing the essential parts arranged in cylindrical form, the insulating-shield and the conducting plates or coatings, however, extending longitudinally instead of horizontally, as in the previous two figures. Fig. 6 is a horizontal sectional view of the construction disclosed in Fig. 5. Fig. 7 is a vertical sectional view showing the practical construction of ozone-tubes according to the present improvements; and Fig. 8 is a horizontal sectional view of the apparatus illustrated in Fig. 7, said section being taken in the plane indicated by the dotted line *x x*.

The relative position of the several parts and the operation of the same is most clearly set forth by the simple form disclosed in Figs. 1 and 2, in which the dielectric plate *c* has two electrical conducting-coatings *a b*, separated from each other by an insulating partition or shield *d*. At the under side of plate *c* and in a slight degree removed therefrom

is the metal plate m , suitably insulated from the plates a b , so that electric discharges take place from the dielectric plate c opposite coating a to the adjacent part of plate m and from the latter to the plate c opposite coating b .

The arrows indicate the direction of circulation of the current of air or gas to be ozonized.

10 In the arrangement disclosed in the third and fourth figures of the drawings, the conductor m is of cylindrical form and is concentrically arranged within the dielectric cylinder c , the cylindrical metal coatings a b being separated by the disk shield or guard d . The guard d may be in the form of two flanges extending diametrically from the dielectric cylinder c and parallel with the axis of the same, in which event the metal coatings or 15 surfaces a b assume the form of semicylindrical sections vertically arranged on the cylinder c on opposite sides of the flanges forming the guard. (See Figs. 5 and 6.)

Heretofore dielectrics have been made almost exclusively of glass or mica. The present improvements contemplate the employment, in addition to the substances mentioned, and particularly for ozone-tubes of large size, all other insulating materials, especially porcelain, earthenware, gelatine, enamel, wood, or paper, (having an insulating material applied thereto or incorporated therewith,) papier-maché, celluloid, gutta-percha, caoutchouc, or ebonite. Those materials that are 25 attacked by ozone may be advantageously protected by being coated with paraffine, to which wax or other cementitious agent is added. The employment of any of said materials in the manner stated will result in an ozone-tube of lightness, durability, and efficiency.

In the practical form of apparatus represented in Figs. 7 and 8 m is a metal tube or cylinder coated with tin or other poor oxidizable metal, and which has secured within it 30 two metal disks t t' . Above the disk t and below disk t' a series of holes ff' are made in the cylinder. End spaces are formed between the disks t t' and cylinder-closing heads m' m^2 , into which latter tubes r r' enter, respectively. Externally on the cylinder m are adjustable rings k k' of ebonite or like material, and which have annular grooves or recesses engaging and retaining the cylindrical sections c c' of dielectric material, 35 metal coatings or plates being applied to the outer surfaces of these sections. The entire structure formed of ebonite rings and sections of dielectric material forms a sleeve tightly fitting around the cylinder m , the middle 40 rings k k' being provided with longitudinal grooves k^2 on their inner surfaces to form channels, through which the two annular spaces between the sleeve and the cylinder can communicate. The fluid to be ozonized 45 passes through pipe r to chamber l_2 from whence it flows through the holes f into the

annular space outside of the cylinder m , after flowing down through such space it enters chamber l' by way of holes f' and is finally discharged through pipe r' . The central space w in the cylinder m can be used for the circulation of a cooling agent, as water, for which pipes s and s' provide for the admission and emission, respectively. The coating a is connected by a wire 2 with one pole of a 50 source of electricity, the coating b being connected by a wire 3 with the other pole of said source. The electric discharge will be from the coating a to the conductor m and from the latter to conductor b , the same as explained with regard to the arrangement illustrated in 55 Figs. 1 and 2.

By vertically dividing the rings and sections of the sleeve the latter may be readily removed or applied without necessitating the disturbance of other parts of the apparatus, and, further, sufficient of the sleeve may be removed to determine the degree of luminosity in the ozonizing-chamber, and hence the relative effectiveness of the ozonizing operation.

The dielectric layer may be mounted directly on the cylinder m , in which event the ozonizing-chamber will be between said layer and the sleeve, the latter simply carrying the outer conducting coatings or plates.

I do not restrict myself to the arrangement by which either the fluid or water may be caused to flow through the apparatus, as the particular mode is immaterial.

The construction and position of the sleeve is such that another may be substituted when necessary.

The electric discharge-currents are designated by 4 in the several figures.

I claim—

1. In ozone apparatus, the combination, with a dielectric layer or plate, of independent electrodes located at one side of the same and a metallic body facing both electrodes, located at the opposite side of and at some distance from the dielectric plate, substantially as described.

2. In ozone apparatus, the combination, with a dielectric layer or plate, of independent electrodes located at one side of the same and insulated from each other by a guard or shield and a metallic body facing both electrodes, located at the opposite side of and at some distance from the said layer or plate, substantially as described.

3. In ozone apparatus, the combination, with a cylindrical metallic body, of a removable sleeve applied thereto to form an ozonizing-space and carrying the conducting-surfaces insulated from each other, together with a dielectric layer located in said ozonizing-space, substantially as described.

4. The combination, in ozone apparatus, of a dielectric layer, independent electrodes at one side of the same, and a metallic body facing both electrodes at the other side thereof, the elements being disposed to present an

ozonizing-chamber, and a cooling-compartment located adjacent to said chamber, substantially as described.

5. The combination, in ozone apparatus, of a cylindrical metallic body, an adjacently-arranged sleeve, and interposed layer of dielectric material, said sleeve being composed of separable parts insulated from each other and each including an independent electrode, substantially as set forth.

6. The combination, in ozone apparatus, of a cylindrical body *m*, having perforations *ff'*, an adjacently-arranged sleeve carrying independent electrodes and forming in part the

15 ozonizing-chamber, with the respective end portions of which the said openings communicate for the circulation of air therethrough, and a layer of dielectric material interposed between the cylindrical body *m* and sleeve, substantially as set forth.

7. The combination, in ozone apparatus, of ring-sections of insulating material and having opposite recesses, independent electrodes and dielectric layers seated in said recesses, the electrode and layer of one section being insulated from those of the other section, and the cylindrical body *m*, arranged at the side of the layers opposite to that occupied by the electrodes, substantially as described.

25 8. The combination, in ozone apparatus, of the headed cylinder *m*, provided with supply and exhaust pipes, respectively, and perforations *ff'*, inner disks *t t'* within the cylinder and inside of the location of the said perforations, said disks having pipes *s* and *s'*, as described, and a sleeve forming an ozonizing-space, with the respective ends of which said openings *ff'* communicate for the circulation of air therethrough, said sleeve comprising

30 rings carrying independent electrodes, together with layers of dielectric material interposed between said electrodes and said cylinder, each electrode and its dielectric material being insulated from the other electrode and its dielectric layer, substantially as set forth. 40 45

9. In ozone apparatus, the combination, with the dielectric layer or plate, of independent electrodes located at one side of the same and a conducting-body facing both electrodes, located at the opposite side of and at some distance from said layer or plate and having a surface of poorly-oxidizable metal, substantially as described.

10. The combination, in ozone apparatus, of a dielectric layer or plate having a surface 55 provided with an ozone-resisting preparation, independent electrodes located at one side of said layer or plate, and a metallic body facing both electrodes, located at the opposite side of and at some distance from the dielectric plate, substantially as described.

11. The combination, in ozone apparatus, of a dielectric layer or plate consisting of a vegetable material having a surface of insulating and ozone-resisting material, independent 65 electrodes located at one side of said layer, and a metallic body facing both electrodes, located at the opposite side of and at some distance from the dielectric plate, substantially as described.

In testimony whereof I have affixed my signature in presence of two witnesses.

OSCAR FRÖLICH.
